FIG. 1

FIG. 2

FIG. 3

FIG. 4

FIG. 5

FIGURE 1 is a front elevational view of a moveable safety gate to aid ingress and egress from a bathtub showing my new design, with center portions broken away to indicate indeterminate length;

FIGURE 2 is a top plan view thereof;

FIGURE 3 is another top plan view thereof showing the gate portion thereof in a different position from that shown in FIGURE 2;

FIGURE 4 is a cross sectional view taken on line 4-4 of FIGURE 1; and

FIGURE 5 is a top plan view of a modified form of the moveable safety gate to aid ingress and egress from a bathtub.

The fragmentary broken line representation of a wall and bathtub in FIGURES 1 and 2 and a wall in FIGURES 3 and 5 are for purposes of illustration only.

I claim:

The ornamental design for a moveable safety gate to aid ingress and egress from a bathtub, substantially as shown and described.
